R. OLDS

MACHINE FOR FLESHING FURRED SKINS

Filed Oct. 12, 1925

Inventor

Richard Olds

by *Ottomar*
his Attorney

UNITED STATES PATENT OFFICE.

RICHARD OLDS, OF WALKERVILLE, SOUTH AUSTRALIA, AUSTRALIA.

MACHINE FOR FLESHING FURRED SKINS.

Application filed October 12, 1925, Serial No. 61,913, and in Australia August 3, 1925.

My invention relates to improvements in machines for fleshing furred skins, the object of the same being to provide means whereby a greater area of the skin can be exposed to the cutting knives than is at present the case with machines at present in use, and also to provide means whereby the depth or thickness of the cut can be evenly adjusted.

- 10 In carrying my invention into effect I provide a cylindrical casing having bearings at each end, but being opened longitudinally at one side. This casing is furnished with a central rotatably mounted spindle upon each 15 end of which there is a spider for carrying a series of helically curved knives arranged somewhat on the well known principle of the knives of a lawn mower. The spindle is mounted on a ball bearing device so that it may 20 rotate with but little friction and can be furnished with a pinion wheel or sprocket wheel or other driving device at one end so that it may receive rotary motion from a driving element.
- 25 Upon each side of the open portion of the cylinder I mount adjustable guides which are capable of sliding in grooves and are adapted to increase or decrease the relatively exposed area of the knives so that the cut 30 can be made from a comparatively slight shaving to any predetermined depth. Provision is made for lubricating the bearings.

But in order that my invention may be more clearly understood I will now describe the same by aid of the accompanying illustrative drawings wherein:—

Fig. 1 is a vertical front elevation of the machine.

Fig. 2 is a sectional plan through the line 40 X—Y of Fig. 1.

Fig. 3 vertical elevation of helical knife.

Fig. 4 end view of knives projected from Fig. 3.

In each of the illustrations similar letters of reference are used to denote similar or corresponding parts wherever they occur.

In the drawings *a* is a bench or platform through which a circular hole is cut as indicated by dotted lines and beneath which a shute *b* is arranged to receive and deflect waste material from the machine.

I construct from sheet metal or malleable cast metal a frame or case *c* preferably of cylindrical formation, a portion of which is open as illustrated in the drawings and along one edge of the open portion I provide a tan-

gential thickening plate *c'*. At the base of the cylinder I form legs or lugs preferably three in number as indicated at *d* through which there is a hole for the foundation bolts *e* whereby it is secured to the bench.

Near to the base of the cylinder I also arrange a lower fixed spider *f* which may form an integral portion of the casing or may be attached thereto by countersunk studs or screws or other convenient means and within this spider I form a cup *f'* to act as a bearing and I provide a ball race therein.

At the top of the structure I arrange a corresponding bearing *g* which may also be provided with a ball race and can be secured by a screw threaded stub *g'* which passes through the top of the structure and is held in position by the nuts *g''*.

For the purpose of mounting the cutting knives I furnish an upper and a lower rotatable spider *h* and *j* having central bearings and being formed with enlarged attachment ends for the knives as indicated at *h'* and *j'* in Fig. 3 of the drawings and being provided with bolts or studs *k* whereby the helical knives *l* are secured to the spiders as illustrated. These knives are preferably three in number and are arranged in the manner illustrated and may have their cutting edges slightly curved in the direction of their traverse as more clearly indicated at *l'* in Fig. 3 of the drawings as is the custom with fleshing knives, the direction of rotation being indicated by the arrows in Figs. 2 and 3.

The upper spider may have a short spindle seated therein adapted to be supported within the upper bearing. The lower spider is keyed or otherwise secured to a spindle *m* which may be adjustably held in position by the nuts *n* and extends downwardly below the bench or platform and is fitted with a bevelled gear wheel *o* which registers with a bevelled gear wheel *p* mounted upon the horizontal driving shaft *q* which is supported by the bracket *r* and receives rotary motion from any convenient source of power. This driving gear, however, may be varied according to preferences and circumstances.

Upon one side of the opening in the frame or case I mount a vertical flat sliding plate *s* having horizontal slots or slideways *s'* near each end thereof, and I also provide projecting studs *t* which are fitted with wing nuts *u* the studs being secured to the frame or case so that the vertical flat sliding plate

when adjusted, can be held in the desired position by the studs and wing nuts as will be readily understood.

Upon the opposite side of the opening I 5 arrange a vertical sliding plate *v* which may be concave so as to fit against the side of the cylindrical frame and is correspondingly provided with slots or openings *v'* and wing nuts *w* adapted to serve as clamps when used in conjunction with the studs or bolts *t*. By means of these sliding plates the effective depth of the cut of the knives can be set according to preferences.

It is to be understood that the knives and 15 the gear wheels can be set so as to rotate in the opposite direction to that which is illustrated in the drawings if, so desired, the sharpening and burring of the fleshing knives being correspondingly adapted.

20 In applying my invention to practical use the machine is set up as illustrated and the vertical flat sliding plates are drawn, backwards or forwards and clamped in position according to the amount of flesh to be removed from the skin or pelt.

The skin is then held by the operator using both hands so that when stretched, cut and drawn tightly across the opening of the machine and allowed to bear against the edges 30 of the sliding plates *s* and *v* the centre of the exposed area lies in the path of the rotating knives so that by drawing the skin or pelt backwards and forwards the flesh will be cut therefrom wherever exposed to 35 the action of the knives. It is intended that the operator should stand between the ma-

chine and the exposed edges of the sliding plates may be suitably bevelled for the more convenient and effective handling of the skin or pelt.

By providing these adjustment plates allowance is thereby made to enable the machine to be adapted to any inequality in the width of the cutting blades due to excessive wear or repeated sharpening, and the blades 45 themselves may be slightly slotted opposite to the bolts or studs *k* so as to enable them to be moved, backwards, or forwards, as may be necessary, and it will be understood that the machine may be varied in size to suit the 50 different classes of skins or pelts which are to be fleshed thereby.

What I claim is:—

1. A fleshing machine having an outer frame or casing and a vertical opening 55 formed therein, vertical adjustment plates mounted on the frame or casing adjacent to each side of the opening, said plates being adapted to slide horizontally for adjustment purposes as described.

2. A fleshing machine as claimed in claim 1, including a series of rotatably mounted knife spiders, and vertical helical knives arranged on the spiders to rotate within the casing, a lower spider fixed within the casing 65 and provided with a central bearing device in which the lower knife spider is journaled.

In testimony whereof I have affixed my signature.

RICHARD OLDS.
